CLAIM

The ornamental design for a closure, as shown and described.

DESCRIPTION

FIG. 1 is an isometric view of a closure according to my new design with its locking cap in the open position.

FIG. 2 is a front view of the closure of FIG. 1.

FIG. 3 is a rear view of the closure of FIG. 1.

FIG. 4 is a right side view of the closure of FIG. 1; the left side view is a minor image.

FIG. 5 is a top view of the closure of FIG. 1.

FIG. 6 is a bottom view of the closure of FIG. 1.

FIG. 7 is an isometric view of a closure of FIG. 1 with its locking cap in the closed position.

FIG. 8 is a front view of the closure of FIG. 7.

FIG. 9 is a rear view of the closure of FIG. 7.

FIG. 10 is a right side view of the closure of FIG. 7; the left side view is a mirror image.

FIG. 11 is a top view of the closure of FIG. 7; and,

FIG. 12 is a bottom view of the closure of FIG. 7.

The portions of the drawings appearing in broken lines are for environment only and do not form a part of the claimed design.
